(57) **CLAIM**

The ornamental design for a control pack, as shown and described herein.

DESCRIPTION

FIG. 1 illustrates a perspective view of a control pack; FIG. 2 illustrates a front view of the control pack as shown in FIG. 1;

FIG. 3 illustrates a top view of the control pack as shown in FIG. 1;

FIG. 4 illustrates a left side view of the control pack as shown in FIG. 1; and,

FIG. 5 illustrates a right side view of the control pack as shown in FIG. 1.

The broken lines illustrate portions of a control pack that form no part of the claimed design.
